US0D1020498S

(12) **United States Design Patent** (10) **Patent No.:** **US D1,020,498 S**
(45) **Date of Patent:** ** *Apr. 2, 2024

(54) **LIQUID GEAR FLOWMETER**

(71) Applicant: **Xiaoying Wu**, Wenzhou (CN)

(72) Inventor: **Xiaoying Wu**, Wenzhou (CN)

(*) Notice: This patent is subject to a terminal disclaimer.

(**) Term: **15 Years**

(21) Appl. No.: **29/815,988**

(22) Filed: **Nov. 18, 2021**

(30) **Foreign Application Priority Data**

Oct. 14, 2021 (CN) 202130674315.5

(51) **LOC (14) Cl.** **10-04**

(52) **U.S. Cl.**

USPC **D10/96**; D23/247

(58) **Field of Classification Search**

(57) **CLAIM**

The ornamental design for a liquid gear flowmeter, as shown and described.

DESCRIPTION

FIG. 1 is a perspective view of a liquid gear flowmeter showing our new design;

FIG. 2 is a front view thereof;

FIG. 3 is a rear view thereof;

FIG. 4 is a left view thereof;

FIG. 5 is a right view thereof;

FIG. 6 is a bottom view thereof; and,

FIG. 7 is a top view thereof.

The broken lines depict portions of the liquid gear flowmeter that form no part of the claimed design.

1 Claim, 7 Drawing Sheets
